UNITED STATES PATENT OFFICE.

PAUL L. PFLAGER, OF CHICAGO, ILLINOIS, ASSIGNOR TO THE PULLMAN COMPANY, OF CHICAGO, ILLINOIS, A CORPORATION OF ILLINOIS.

AXLE-GENERATOR SUPPORT.

1,112,831.

Specification of Letters Patent.

Patented Oct. 6, 1914.

Application filed March 31, 1913. Serial No. 757,879.

To all whom it may concern:

Be it known that I, PAUL L. PFLAGER, a citizen of the United States of America, and resident of Chicago, Cook county, Illinois, have invented a certain new and useful Improvement in Axle-Generator Supports, of which the following is a specification.

My invention relates to improved means for supporting axle generators on a car truck. These generators are usually mounted on a frame suspended from the car truck and adjacent to the car axle, whereby the generator can be driven from power derived from the axle. In prior constructions difficulty has been experienced in these supports, owing to the number of wearing parts.

One of the objects of my invention is to provide a support in which these wearing parts are reduced to a minimum, and in which the support consists of a single integral casting secured to the frame of the car truck. These and other objects of my invention will be more clearly understood by having reference to the accompanying drawings in which I have illustrated one embodiment of my invention, although, of course, it will be understood that my invention is not limited to the particular shape and form of the casting shown in these drawings, but that various modifications can be made and still come within the scope of my invention.

Figure 1 is a plan view of my improved support. Fig. 2 is a sectional view taken on the line 2—2 in Fig. 1. Fig. 3 is an end view of the device. Fig. 4 is a detailed side view of the frame. Figs. 5 and 6 are detail views.

I represent a portion of the frame of the car truck, which frame consists of the side sills 7 and 8 and the end sill 9 and the intermediate longitudinal braces 10 and 11. In the usual construction the end sill dips downward, as indicated in Fig. 3, and the car axle is supported in suitable bearings hung from the side frames, as indicated in Fig. 2.

In the usual construction the axle generator is located outside of the end sill and driven by a belt on a pulley on the car axle. In order to so mount the generator, I provide an integral casting 13 which is rectangular in shape, as shown in Fig. 1, and also dips downward, as shown in Fig. 4. This casting is provided with two supporting ex-

tensions 14 and 15, which are securely bolted to the intermediate bars 10 and 11. As shown, these arms are set inward to a slight degree, this being for the reason that it is necessary for the casting to clear the brake release springs 16. Of course, if these springs were set inward farther on the end sill, it would not be necessary to offset the casting in this manner. Connecting the two lower horizontal side sections of this casting are a pair of brace bars 17 and 18. These side members of the casting are provided with rectangular openings 19 within which are located alining blocks 20. These alining blocks are provided with a central portion which provides a bearing 21 for the rock shaft 22. These spacing blocks are secured to the casting 13 by means of the bolts and nuts 23. The axle generator 24 is mounted upon this rock shaft 22 in the well known manner, being provided with a pair of downwardly extending legs 25 through which the rock shaft 22 passes. The generator pulley 26 is connected with the axle pulley 27 by means of the belt 28, whereby power is transmitted from the axle to the generator. In order to properly aline the generator pulley with the axle pulley it is merely necessary to properly adjust the alinement blocks 20 within the frame 13. In order to mount the generator securely upon this rock shaft 22, I provide any suitable means, such as a tension rod 30 which passes through an opening in the casting 31 carried by the rear connecting bar of the supporting casting and is secured at its forward end to the frame of the axle generator. A spring 32 is mounted on this rod, and this rod is threaded and provided with an adjustable nut 33 which bears against the spring, whereby on tightening this nut the generator can be rocked backward so as to tighten the bolt 28, while when the nut is loosened the spring tension forces the generator in the opposite direction to loosen the belt.

While I have shown one particular means for holding the generator in place on the rock shaft, it is, of course, understood that any suitable means can be employed for this purpose.

In order to make a more rigid connection between the support 13 and the car truck frame, I provide an offset portion 29 which is adapted to extend beneath the end sill 9.

and thus grip the same, and in this manner providing a very rigid and efficient support for the axle generator.

It will thus be seen that I have devised a very simple support comprising a single integral casting, and in which substantially all the wearing parts are eliminated. The only wear would occur on the bearing for the rock shaft 21 in the alinement blocks 20, 13 and in the usual construction a bushing is provided which surrounds this shaft whereby the entire wear comes on this bushing.

While I have illustrated and described one particular embodiment of my invention, it 15 will be understood that I do not wish to be limited to the exact construction shown and described.

What I claim as my invention is:

1. In a car truck, a frame, an axle generator, and a support for said generator carried by said frame, said support consisting of a single integral casting independent of said frame.

2. In a car truck, a frame, a single integral casting secured to said frame, a rock shaft mounted in said casting, and an axle generator mounted on said rock shaft, said casting being independent of said frame.

3. In a car truck, a frame, a single integral casting secured to said frame, a rock shaft mounted in said casting, an axle generator mounted on said rock shaft, and means for adjusting the position of said rock shaft in said casting to properly align said axle generator, said casting being independent of said frame.

4. In a car truck, a frame, an integral casting secured to said frame, said casting comprising a pair of members spaced apart, 40 downwardly curved and longitudinally extending side members, an end member extending between said side members, a rock shaft carried by said frame, and an axle generator carried by said rock shaft.

45 5. In a car truck, a frame comprising side members and an end sill, an axle generator support secured to said frame, said support comprising a pair of supporting members secured to said frame, downwardly and rearwardly extending side members, brace bars securing said side members together, a rock shaft mounted in said side members, and an axle generator mounted on said rock shaft.

55 6. In a car truck, a frame comprising side members and an end sill, an axle generator support secured to said frame, said support comprising a pair of supporting members secured to said frame, downwardly and rearwardly extending side members, brace bars securing said side members together, a rock shaft mounted in said side members, and an axle generator mounted on said rock

shaft, and means for adjusting the position of said rock shaft in said side members.

7. In a car truck, a frame, an axle generator support secured thereto, said support comprising side members spaced apart and secured at their ends to said frame, said members extending downwardly and rearwardly, and provided with an extending lug 70 for gripping said end sill, and a shaft carried by said members, and an axle generator support mounted on said shaft.

8. In a car truck, a frame, an axle generator support secured thereto, said support 75 comprising side members spaced apart and secured at their ends to said frame, said members extending downwardly and rearwardly and provided with an extending lug for gripping said end sill, a shaft carried by 80 said members, an axle generator support mounted on said shaft, and means for adjusting the position of said shaft in said members.

9. In a car truck, a frame comprising 85 side and end sills, an axle generator support secured thereto, said support comprising an integral casting consisting of a pair of spaced side members, an end member connecting said side members, said side members extending downwardly and provided with a notched portion adapted to grip the end sill, means for securing said casting to the frame, and an axle generator supported in said casting. 95

10. In a car truck, a frame comprising side and end sills, an axle generator support secured thereto, said support comprising an integral casting consisting of a pair of spaced side members and an end member 100 connecting said side members, said side members extending downwardly and provided with a notched portion adapted to grip the end sill, means for securing said casting to the frame, a rock shaft mounted 105 in said casting, an axle generator mounted on said rock shaft, and means for adjusting the position of said rock shaft in said support.

11. In a car truck, a frame, an integral 110 casting secured to said frame, said casting comprising a pair of members spaced apart, downwardly curved and longitudinally extending side members, an end member extending between said side members, and an 115 axle generator supported by said integral casting.

Signed by me at Chicago, Illinois, this 29 day of March, 1913.

PAUL L. PFLAGER.
